UNITED STATES PATENT OFFICE.

JOHN D. LEE, OF CLEBURNE, TEXAS.

CUSHION INSOLE AND ARCH-SUPPORT.

1,125,134.

Specification of Letters Patent. Patented Jan. 19, 1915.

Application filed April 23, 1914. Serial No. 833,830.

To all whom it may concern:

Be it known that I, JOHN D. LEE, a citizen of the United States, residing at Cleburne, in the county of Johnson and State of Texas, have invented certain new and useful Improvements in Cushion Insoles and Arch-Supports, of which the following is a specification.

My invention relates to new and useful improvements in a combined cushion in-sole and arch support, and it is the object of the invention to provide a device of this character that will form a complete interior lining for the sole of a shoe extending from toe to heel thereof, the middle portion of the device being formed of an increased thickness to constitute the arch support.

It is a further object of the invention to provide a cushion in-sole and arch support, which by furnishing a support for the middle portion of the foot as well as for the ball thereof will relieve the ball of the foot to some extent of the weight which it would otherwise carry, and will thus materially decrease the possibility of corns or bunions forming on the ball of the foot.

A still further object of my invention is to provide a device of the character described, which will tend to maintain a certain circulation of air when a person using the device is walking, thus tending to maintain the feet in a more comfortable and sanitary condition.

Finally the object is to provide a device of the character described, that will be strong, durable, simple and efficient and comparatively inexpensive to produce.

With these and various other objects in view, my invention has relation to certain novel features of the construction and use, an example of which is described in the following specification, and is illustrated in the accompanying drawing, wherein:

Figure 1 is a bottom view of my combined cushion in-sole and arch support. Fig. 2 is a top view of the same. Fig. 3 is a longitudinal vertical sectional view taken upon the line *a—a* of Fig. 1. Figs. 4, 5 and 6 are transverse vertical sectional views, respectively taken upon the lines *b—b*, *c—c* and *d—d* of Fig. 1.

Referring now more particularly to the drawing, wherein like reference characters designate similar parts in all the figures, the numerals 1 and 2 respectively denote a top and a bottom member which together

constitute my invention, said members having a shape conforming to that of the sole of a shoe, and being permanently connected in a rigid relation preferably by some adhesive as cement. The upper member 1 is to be formed preferably of leather and is of the same thickness throughout. The lower member 2 constitutes the cushion portion of the device and hence will preferably be formed of sponge rubber. That portion of the member 2 which is intended to occupy a position beneath the ball and sole of a person's foot is perforated throughout its entire area as indicated at 3. The heel portion and middle of the member 2 have a plurality of rectangular cushions 4 formed upon their under surface, said cushions being produced by two series of V-shaped grooves in said surface intersecting each other at right angles, as indicated at 5. The member 2 has a maximum thickness midway between its extremities and adjacent to that lateral edge which in the use of the device will come beneath the inner side of the arch of a person's foot. From this point the member 2 reduces gradually in thickness toward its other side and toward its extremities. By giving the device this peculiar shape, it is made to conform substantially to the natural shape of the sole of one's foot, so that the foot may rest upon the device comfortably and securely. The portion of the weight ordinarily transmitted to the sole of a shoe through the ball of a person's foot will in the use of my device be carried by the portion thereof having the greatest thickness, so that the ball of the foot being relieved of a portion of its weight will be less subject to corns or bunions.

In order that air may circulate vertically to some extent through the device, a plurality of small orifices 6 are formed in the member 1, some of these orifices being alined with certain of the perforations 3, and others being extended through the member 2 into communication with certain of the grooves 5.

When a person using a pair of my improved in-soles in his shoes is walking, the cushions are compressed each time they are subjected to the weight of a person's foot, and when the foot is again raised, said cushions will expand. This alternate compression and expansion of the cushions 4 will tend to maintain a circulation of air back and forth through the apertures 3 and 6, and this ventilation will be beneficial both

from the view point of sanitation and comfort. The cushion effect afforded by the use of my device will give elasticity to the walk, counteract the effect of the hard pavement, and materially add to the comfort of a pedestrian.

It is to be observed that a transversely elongated strip 7 which is embodied in the member 2 between its perforated and its 10 grooved portion has a considerable thickness, this strip being of importance since the portion of the weight ordinarily upheld by the ball of the foot will in the use of my invention come upon said strip.

15 The invention is presented as including all such modifications and changes as properly come within the scope of the device as claimed.

What I claim is:

20 1. A cushion in-sole and arch support, comprising rigidly connected upper and lower members conforming to the shape of the sole of a shoe, the lower member being formed of sponge rubber, its forward portion being perforated, and its rear and intermediate portions being formed upon the underside with a plurality of rectangular cushions.

25 2. A cushion in-sole and arch support comprising rigidly connected upper and lower members conforming to the shape of the sole of a shoe, and the upper member being perforated, the lower member having aper-

tures and formed of sponge rubber and having its forward portion perforated, and its 35 rear and middle portion formed with rectangular cushions upon the under surface, certain of the perforations being alined with apertures in the upper member, said apertures also being extended through the two 40 members at their rear and intermediate portions.

3. A cushion in-sole and arch support comprising rigidly connected upper and lower members, conforming to the shape of 45 the sole of a shoe, the upper member having apertures, the lower member being formed of rubber and having a varying thickness, the greatest thickness being midway between its ends and adjacent to one side, from 50 which point it reduces gradually in thickness toward the other side and toward both ends, said lower member being perforated in its front portion, and having its rear portion formed upon its under surface with a 55 plurality of cushions, certain apertures in the upper member being alined with certain of the perforations in the lower member.

In testimony whereof I have signed my name to this specification in the presence of 60 two subscribing witnesses.

JOHN D. LEE.
